UNITED STATES PATENT OFFICE

MICHAEL T. O'DONNELL, OF DULUTH, MINNESOTA

DISPLAY CASE

Application filed October 3, 1930. Serial No. 486,125.

This invention relates to transferable display cabinets, and has special reference to a display cabinet or case for use in and about garage buildings or the like, and designed

5 particularly for the purpose of displaying either externally or internally of the building the commodities for sale at the garage.

The principal object is to produce a simple receptacle and means for securely supporting same in locked relation to the support in either of several selective places.

10 Other objects and advantages of the novel structure will appear in the further description of the invention.

15 Referring now to the accompanying drawing wherein like reference characters indicate like parts:

Figure 1 is a perspective view of a cabinet embodying the invention and in position 20 upon one of its supports;

Figure 2 is a somewhat enlarged perspective view of the attaching strip on the back of the cabinet;

25 Figure 3 is a similar view partly broken away of the holder or keeper; and

Figure 4 represents the U-shaped bands found in connection with gas station service pumps.

The display cabinet, here shown as rectangular in form as a preferred shape, is illustrated at 1, and is provided with an inwardly recessed door 2, having a glass panel therein through which the contents of the cabinet may readily be seen.

30 35 The door is recessed within the front wall of the cabinet to overcome the danger of wetting the interior in the event of stormy weather, or the like, when the cabinet is supported externally of the building, and is provided with a suitable lock.

Upon the back of the case is fixed in any desired manner as by suitable bolts through the holes 3 the bent depending strip 4 which when attached to the cabinet is spaced slightly from the back thereof. The lower portion 45 of the strip 4 is bent outwardly at right angles forming a narrow shelf or floor like portion 5, and thence upwardly and inwardly as at 6 and fixed to the body portion of the strip, but may, if desired, extend the full

length thereof for strength. Through the floor 5 is formed a slot 7 for cooperative engagement with the lock hereinafter described.

The support proper for the cabinet shown in Figure 3 at 8, is of sheet metal and of channel-like form sufficiently deep for the reception of the strip 4 on the back of the cabinet. This supporting member is provided with laterally projecting flanges 9 having a plurality of holes 10 therein for attachment to the wall of a building, or if so preferred to the termini of the U-shaped bands 11, illustrated in Figure 4, which are frequently found associated with the dispensing pumps. Obviously by either of these latter described means the cabinet may be displayed where readily seen by those passing or availing themselves of service at the garage.

70 The lower end of the channel holder 8 is provided with a transverse shelf like member 12 fixed interiorly thereof and which member carries a suitable lock 13 which I have illustrated as being similar to those found on roll top desks or the like; the same being provided with laterally projecting catches 14 which in this instance occur above the shelf 12 and are cooperatively engageable with the slot 7 in the strip 4 previously described.

75 Access to the lock 13 is had through any suitable escutcheon 15 on the lower face of the holder 8, and which latter extends materially below the cabinet 1 for convenient accessibility.

80 From the foregoing it is evident that I have devised an exceedingly simple and effective display cabinet which may readily be transferred from one holder to another and answer the purpose for which it is intended admirably.

85 Having thus described my invention, what I claim and desire to secure by Letters Patent, is:

90 95 1. In combination, a receptacle having fixed adjacent the upper edge of the back thereof a depending strip spaced therefrom, and a channel like support for cooperative engagement with said strip the latter slid- 100

ably extending within the channel, and means accessible beneath the receptacle for automatically locking the support and receptacle together.

5 2. In combination, a channel like supporting member having a lock in the bottom thereof and an open upper extremity, a co-operative strip for attachment to a portable object having at its lower extremity means
10 for cooperative engagement with the lock in the support and vertically slidably therein, said means being accessible from beneath the object.

In testimony whereof I affix my signature.

15 MICHAEL T. O'DONNELL.
